Attorney

UNITED STATES PATENT OFFICE.

OTTO MICHALK, OF FREITAL, NEAR DRESDEN, GERMANY.

PRESSURE-APPLYING AIR PAD.

Application filed November 3, 1928, Serial No. 316,924, and in Germany September 3, 1928.

In the manufacture of shoes by the cementing method, more particularly fancy shoes, air pressure pads are almost exclusively used. They contain a flat rubber bladder 5 sewn into a leather bag. The use of these pressure applying pads has the disadvantage that in consequence of the pressing pressure the heel cap of the shoe is forced out sideways at its periphery and that the sole is forced up at the toe, the ball and the heel 10 of the shoe. This entails additional work during the manufacturing process, involving additional expanse, in order to make the shoe salable.

15 The present invention overcomes this difficulty by the sole which is to be stuck on not being cemented on at all at the heel part in the same operation and the forcing up of the sole at its edges being prevented. The 20 pressure-applying pad therefore extends only along the sole and the instep of the shoe, thus ending in front of the heel. In addition to this the pressure-applying pad is stiffened over the rubber bladder by a reinforcing sole 25 which is chamfered off at the end of the ball, thus providing a gradual transition to the softer part of the bag of the pad at the instep. The stiffening sole might however be extended under the instep by a sole of 30 soft leather joined to it in a suitable manner by cementing the parts together.

The accompanying drawing shows a constructional example of the invention, Fig. 1 being a plan view of the pressure applying pad with a sole indicated above it.

35 Fig. 2 a longitudinal section through the pad on line 2—2 of Fig. 1, and

Fig. 3 a cross-section on line 3—3 of Fig.

1.

40 Fig. 4 is a longitudinal section similar to Fig. 2 through another constructional form.

The pressure-applying air pad consists of the leather bag formed by the layers *f*, *f'* and the edge strip *h*, marginally sewn together 45 and of a rubber bladder *g* inserted in the hollow space between them and having a valve *g'* extending to the outside. The pad bag is usually reinforced by an upper layer of leather *i*. In order that the heel portion 50 shall not have pressure applied to it during the cementing operation, the pad bag ex-

tends only three-quarters of the length of the sole, namely up to the line *b*—*b* in Fig. 1, thus ending immediately adjacent the heel or the heel part *d'* of the sole *d*. The heel 55 part *d'* will therefore not be cemented on, but may be nailed or otherwise secured to the sole. On the side facing the outer sole the pressure applying pad is stiffened by a leather insertion *k* which is chamfered off at 60 the end of the ball point, say between the lines *x*—*x* and *y*—*y*, so that it merges gradually into the part of the pad bag under the portion *d''* of the sole and which forms the 65 instep of the shoe. This insertion may be placed inside the bag, i. e., between the two protective covers *f'* and *i* or on the outside of the bag. When the pressure is applied, the insertion *k* prevents the edge *l* of the sole *d* from being pressed against the shoe *m*. 70

In order to give the pressure-applying bag a flat surface, the insertion *k* may be continued as an insertion *k'* of soft leather, which extends beyond the instep *d''* so that the rubber bladder *g* when inflated can expand sufficiently at this point and apply pressure to the instep. 75

I claim:

1. A pressure-applying air pad for shoe cementing air presses, comprising a leather 80 bag, a rubber bladder enclosed in said bag, means for inflating said bladder, a reinforcing layer for said bag, all the said bag, bladder, said layer being of a length to extend over the sole part and instep of the shoe only, 85 and to end short of the heel part, substantially as described.

2. A pressure-applying air pad for shoe cementing air presses, comprising a leather bag, a rubber bladder enclosed in said bag, 90 means for inflating said bladder, a reinforcing layer for said bag, the said bag, bladder, and layer being of a length to extend over the sole part and instep of the shoe only, and to end short of the heel part, and an 95 additional stiffening leather layer arranged to extend over the sole part of the shoe and chamfered off at a point coinciding with the end of the ball of the shoe, substantially as described.

3. A pressure-applying air pad for shoe cementing air presses, comprising a leather 100

bag, a rubber bladder enclosed in said bag, means for inflating said bladder, a reinforcing layer for said bag, the said bag, bladder and layer being of a length to extend over the sole part and instep of the shoe only, and to end short of the heel part, an additional stiffening leather layer ar-

ranged to extend over the sole part of the shoe and chamfered off at a point coinciding with the end of the ball of the shoe, and a soft leather extension applied to said stiffening leather layer, substantially as described. In testimony whereof I affix my signature.

OTTO MICHALK.
